HOT-WIRE CLAMP

Henry W. Bodendieck, Taylorville, Ill.

Application May 24, 1948, Serial No. 28,906

10 Claims. (Cl. 173—273)

1

The present invention relates to hot wire clamps, and is particularly concerned with electrical connectors of the type adapted to be used in connecting transformer leads, jumper leads, or any other connections which may be made to a transmission line or from one line to another, on lines which may be energized or deenergized.

The present application is a continuation in part of my prior application, Serial No. 636,655, filed December 21, 1945, for Hot wire clamps.

One of the objects of the invention is the provision of an improved electrical connector of the clamp type which is spring actuated in one direction and which is adapted to be actuated in the other direction by means of a cam, in such manner that it is unnecessary to utilize any threaded parts.

The ordinary spring type clamps of the prior art have been unsatisfactory, and, therefore, they have been for the most part superseded by connector clamps utilizing threaded members for opening and closing the jaws of a connector upon an electrical wire. These threaded members were necessary to secure sufficient pressure and to maintain the pressure on an electric wire to reduce the contact resistance and carry the current load which is imposed upon such connectors.

Where screw type clamps are used, experience has proven that these clamps are unsatisfactory, particularly where they are used in service out of doors near the coast lines, where the atmosphere contains salt, or in the neighborhood of industrial establishments, where the atmosphere contains acid fumes. Both of these atmospheric conditions result in corrosion within the cut threads, and in a short time this makes the threaded portions inoperable and unfit to perform all of the uses intended for the clamp.

In other locations where vibration is excessive upon the conductor to which the connector is applied, the threaded screw vibrates loose, causing a loose connection and damage to the electrical conductor, which may cause serious delays and breakdown of transmission lines, and the like.

The spring type clamps of the prior art with which I am familiar were not provided with any operating means for opening the jaws of the clamp, and the jaws were forced apart by the camming action of the transmission line conductor as it pushed into the clamp, due to the operator pulling downward on the clamp.

In such connectors, if the springs were made of pressure great enough to warrant a firm contact on the line for carrying current and for preventing endwise shift upon the conductor, it then became very difficult and in most cases impossible

2

to apply the clamp to electrical conductors. The stiffer the spring, the harder it was to force the jaws apart by pressing them against the transmission line conductor. Furthermore, it was not desirable to place the strains on the transmission line conductors which were involved in forcing the spring clamps of the prior art open in this manner by pushing them against the line.

One of the objects of the present invention is the provision of an improved type of clamp or connector which permits the operator to install the clamp upon a conductor, either energized or deenergized, safely and easily, and which eliminates any possibility of the clamp loosening on the line through vibration or any possibility of the freezing of the clamp by corrosion of threads caused by atmospheric conditions.

Another object of the invention is the provision of an improved operating means for clamping connectors of the type described which is not subject to any of the disadvantages of threaded operators, and which will open or close the jaws under high resilient pressure without imposing any substantial strains upon the transmission line.

Another object of the invention is the provision of any improved hot wire clamp, which may be provided with any of a plurality of different operating members, such as an operating member permanently attached to an insulating pole, an operating member having a handle to be manipulated with the hands wearing gloves, an operating member having an eye of the type gripped by clamp sticks, or an operating member having a slotted flange to be adjustably secured to the so-called "Universal" pole.

Another object of the invention is the provision of an improved clamp of the class described which has a three point pressure contact upon the conductor, and which will accommodate various sizes of wires, the three point contact jaws providing more contact area and better rigidity on the conductor, and avoiding marring of the lines or the possibility of any undue movement either endwise or up or down, thus adding materially to the life of the conductor and to the satisfactory operation of the clamp.

Another object of the invention is the provision of an improved spring pressed hot wire clamp, which is provided with a cam actuator for opening and closing the clamp, in which provision is made to prevent the rattling or vibration of the actuator with respect to the hot wire clamp, after the clamp is engaging a line conductor and pressure has been removed from the cam by such

engagement so that there will be no danger of static due to such rattling.

Another object of the invention is the provision of a plurality of different forms of hot wire clamps of the class described, which are sturdy, simple, capable of economical manufacture, and adapted to be used under the most adverse conditions without possibility of corrosion affecting their operating characteristics or freezing them on the line, or any possibility of their becoming loose inadvertently.

Other objects and advantages of the invention will be apparent from the following description and the accompanying drawings, in which similar characters of reference indicate similar parts throughout the several views.

Referring to the three sheets of drawings accompanying this specification,

Fig. 1 is a fragmentary side elevational view of a hot wire clamp embodying the invention shown in connection with a clamp stick, the clamp being in closed position;

Fig. 2 is a rear elevational view of the same clamp without the clamp stick;

Fig. 3 is a sectional view taken on the plane of the line 3—3 of Figure 2, looking in the direction of the arrows;

Fig. 4 is a side elevational view in partial section on a plane which passes through the axis of the operating member with the clamp in the open position;

Fig. 5 is a fragmentary sectional view taken on the plane of the line 5—5 of Figure 4, looking in the direction of the arrows and showing the position of the parts at the time of assembly;

Fig. 6 is a view similar to Figure 4 of a modification in which the operating member is freely removable from the hot wire clamp when it has been clamped on the line;

Fig. 7 is a view in perspective of an operating member for a hot wire clamp of the class described, which operating member is removable from the clamp as a unit and which is provided with an eye structure of the type adapted to be received in a clamp stick;

Fig. 8 is a fragmentary view in perspective of the lower portion of another form of operating member intended to be actuated with the hand, using gloves if the line is energized with a low voltage;

Fig. 9 is a fragmentary view in perspective of the lower part of another operating member of a type permanently secured to the end of an elongated wooden insulating pole;

Fig. 10 is a fragmentary view in perspective of the lower end of another modified form of operating member, which is adapted to be removably secured to the upper end of an insulating pole of the "Universal" type, which is equipped with a flange and a clamping bolt on its upper end;

Fig. 11 is a view similar to Figure 5, showing the arrangement of these parts for a removable operator of the type of Figure 6; and

Fig. 12 is a view in perspective of the operator member of Figure 6.

Referring to Figures 1 to 6, these are views of a hot wire clamp, which is provided with an operating member equipped at its lower end with an eye structure of the same size as is usually employed upon the ordinary hot wire clamps of the prior art. The size of such eye structures is standard so that they may all be engaged by the various clamp sticks made by different manufacturers. I desire it to be understood, how-

ever, that the present hot wire clamp may be provided with any of the operating members which are shown in Figures 7 to 10, and which differ mainly in the shape of the lower end of the operating member.

For example, the operating member 20 of Figure 7 has its shank 21 provided with a standard eye 22, of such a size as can be engaged by an ordinary clamp stick.

10 The same operating member might be equipped with the formation shown in Figure 8, in which the shank 21a is provided with an integral transverse cylindrical bar or handle 23, preferably having ball-shaped formations 24 at each end. 15 Such an operating member as shown in Figure 8 may be actuated by direct engagement with the hand when not energized, but when it is applied to energized conductors, preferably of low voltage, the lineman should wear a rubber glove, and this type of operator should never be employed for high voltage lines.

Referring to Figure 9, in this case the shank 21b is integrally attached to the end wall 25 of a metal ferrule 26. The metal ferrule 26 has a cylindrical body 27, with a cylindrical bore 28 fitting on the end of an elongated insulated pole 29, to which it is permanently attached by a transverse pin 30. The pin 30 passes through the ferrule and the pole and is riveted over at both ends.

30 Referring to Figure 10, this is another modified structure for the lower end of the operating member, of the type adapted to be attached to the so-called "Universal" pole. In this case the shank 21c has a flattened disc-like portion 31, which is provided on one side with a plurality of radial teeth 32.

A slot 33, having a circular base 34, extends inwardly from the end of this operating member 40 for passing a screw bolt on the "Universal" pole. As is well known, the "Universal" pole has its upper end provided with a circular flange into which a screw bolt is threaded, and the flange 31 of the operator of Figure 10 may have the screw bolt located in the slot 33 and may be clamped to the "Universal" pole in any one of a multiplicity of different angular positions. Of course the axial position is the proper one when an operator is to be rotated by means of the pole.

50 Referring now again to the devices of Figures 1 to 6, the lower end of the operating member used in these hot wire clamps may be varied, as shown in Figures 7 to 10. Additional variations may be made by making the heads on the shanks of different shape, such as square, hexagonal, etc., (not shown) but these shapes are not commonly used.

The operating members for the hot wire clamps are preferably provided with an enlarged cylindrical portion 35, and with a thrust bearing flange 36, carried by the enlargement 35 and comprising a substantially circular flange.

The thrust bearing flange 36 is preferably cut away and provided with a radial slot 37 on one side, as shown in Figure 5, for the purpose of permitting the assembly or separation of the operating member 20 from the hot wire clamp.

70 The hot wire clamp 38, shown in Figures 1 to 5, preferably include a fixed jaw member 39 and a movable jaw member 40. The fixed jaw member 39 may have its main body of substantially T-shape in cross-section, including a rearwardly projecting rib 41 carried by a flat body 42.

The rearwardly projecting rib 41 may carry 75 a diagonally extending lug 43, which extends to-

ward the cylindrical enlargement 35, and has an upper flat thrust surface 44 engaging the lower surface 45 of the thrust flange 36.

In its operation, opening or shutting the hot wire clamp, the operator 20 is urged downwardly in Figure 1 by the movable jaw and its spring, and this movement is resisted by the thrust surface 45 engaging the stop surface 44 on lug 43 over a wide range of movement comprising substantially 270 degrees.

The slot 37, Figure 5, is, however, adapted to pass the lug 43 when the jaws are opened by some other means, such as a prying member or a tool of suitable thickness to hold the jaws open. Then the operating member 20 may be rotated until the slot 37 registers with the lug 43, and the parts are in position to remove or insert the operating member 20.

Rotation of the operating member is also preferably limited by providing the thrust flange 36 with a further radial extension 46, Figure 5, which engages the side of the rib 41 at the slot 47, Figure 1, which extends into the rib 41 sufficiently to provide space for the rotation of the main part of the circular thrust flange 36.

The stop extension 46 prevents the user from rotating the operating member 20 so far that the cam might pass off the follower. In addition to the thrust flange 36, which extends at right angles to the axis of the shank 21 of operator 20, the said shank carries a cam flange 48 above the thrust flange 36, and the cam flange 48 in this embodiment of the invention may be of uniform radial size, but the cam flange 48 changes its axial location gradually from the point 49, Figure 7, to the point 50, which may be at about 90 degrees from the point 49 in a rotative direction.

The intervening part 51 of the cam may be called the rise of the cam, and it is also shown in Figure 1 between the points 50 and 49. The remaining portion 52 of the cam has very little or no slope, and may be called the dwell of the cam 48, as it is substantially at right angles to the axis of the shank 21.

At its beginning 49, the rise 51 of the cam is integrally attached to the thrust disc 36 adjacent the clearance slot 37. At its other end, that is, the end of the dwell 52, the cam 48 is formed with a stop surface 53 which is curved to fit against the adjacent side and stop surface 54 of an inwardly projecting lug 55, Figure 3, on the movable jaw, this lug also having end surfaces 56 which serve as a follower for the cam 48, and are carried by the movable jaw 40 so that the cam may engage and move the movable jaw.

At its upper end, beyond the cam 48, the operating member 20 is provided with a cylindrical shank extension 57 which serves as a shaft or trunnion, being rotatably mounted in the bearing bore 58 of an integral bearing formation 59, which forms a part of the fixed body 39.

The shaft extension 57 of the shank preferably has a flat end 60 for engagement with a compression spring 61 of helical form, the other end of which engages the base 62 of the bore 58. The purpose of the compression spring 61 is to urge the operating member 20 axially in its bearing bore 58 to keep the thrust flange 36, with its lower surface 45 engaging the top 44 of stop lug 43. This prevents rattling of the operator on the clamp assembly when the clamp has been installed upon a conductor.

Without the spring 61, the slight amount of end play, which is produced by ordinary manufacturing variations, permits the operator 20 to be

slightly loose after the tension of the clamp spring 63 is released by the line conductor between the clamping jaws.

The elimination of rattling is highly desirable because it might cause static disturbances that might interfere with radio reception, etc.

Referring to Figure 7, this is another form of operating member different from that of Figures 1 to 4, in that it may be used with a hot wire 10 clamp having a through bore at 58, or a bore at least of sufficient length to receive the shank extension 64. In this case the operating member is intended to be removed when the clamp is installed on a transmission line conductor, and the end of the shank extension 64 is pointed or tapered slightly at 65 for convenient reinsertion in the bore 58 when the hot wire clamp is again to be removed.

In order to permit the removal of this operator of Figure 7, its clearance slot 66 is so located that with the clamp in the closed position the slot 66 already registers with the lug 43, and the cam flange 48 is also recessed at 67 to clear the follower, such as the follower 68 of Figure 6, at this time.

Thus there is only a slight difference between the removable operator of Figures 6 and 7 and the operator of Figures 1 to 4, which is intended to remain attached to the hot wire clamp. The removable operator clamp of Figure 6 has the advantage that only one operator need be provided for a multiplicity of clamps. This reduces the number of parts for the clamp by one and reduces their cost, and it prevents anyone who does not possess such an operator from tampering with the clamp on the line.

The fixed jaw member 39 is preferably provided with an electrical connector at its lower end, and this may consist of an apertured extension 69, Figure 4, which is provided with a through bore 70 for receiving a headed screw bolt 71. The extension 69 is formed on its right side, in Figure 4, with an upper and lower V-shaped groove 72, 73 above and below the bore 70.

Above the grooved portion 72 the body extension 69 carries a transversely extending flat stop flange 74, which is adapted to engage the end of the tap wire 75 to limit its insertion into the connector.

At the right end of the through bore 70 there is an enlargement which is partially spherical at 76 for receiving the circular enlargement 77 on the bolt 71. This circular enlargement has a through bore 78 for receiving the tap wire 75, and the screw bolt 71 preferably has an elongated head 79. The elongated head 79 preferably has V-shaped grooves 80 on the side toward the tap wire 75 above and below the bore 78, Figure 4.

The shank 81 of the screw bolt 71 is threaded to receive a nut 82, which engages a spring lock washer 83 and reacts against a flat surface 84 on the body extension 69. Thus a tap wire 75 may be inserted in the hole 78 of the bolt 71 from below until it hits the stop flange 74. A tightening of the bolt nut 82 will cause the tap wire 75 to be clamped between the V-shaped grooves 73 and 80, giving four line contacts between the connector and the cylindrical tap wire 75.

The length of the contact is substantial so that contact resistance is reduced to a minimum. The head 79 of the screw bolt 71 is preferably convexly curved from top to bottom and provided with an outwardly projecting rib 99, which projects above the stop flange 74 and streamlines the entry into the space between the jaws, as shown

in Figure 4. Thus there is no chance of the conductor catching on the head of the bolt 71 or the stop flange 74 as the clamp is put on the line.

The movable jaw 40 is preferably formed at its lower end, Figure 1, with a diagonally extending guide nose 85, Figure 1, the lower surface 86 of which aids in guiding the line conductor into the space between the two clamping members. This guide nose 85 may be in the form of a half-ring having a pair of forwardly extending side portions 87 and a transverse portion 88. The aperture in this half-ring serves the useful purpose of saving material and clearing the stop flange 74.

The guide nose 85 is integrally supported upon a V-shaped clamping formation 89, which has a transversely extending V-shaped trough 90 on the side toward the fixed clamping member 39. The trough 90 is adapted to receive the line conductor and to clamp it against the relatively flat opposed clamping surface 91 on the fixed clamping member 39.

This gives a three-line contact between the line conductor and the hot wire clamp. The transverse length of the clamping surface 91, and the transverse length of the trough 90 is such that there is an extended contact area, reducing contact resistance. The contact 91 may be convexly curved from left to right. The body 69 may be provided with a partially cylindrical groove 134, Figure 4, for receiving the lower corner 135 of the trough member 89, thus permitting the clamp to close on smaller wires.

The fixed jaw member 39 preferably has a substantially rectangular body extending upwardly from the contact surface 91, and this body may be provided with a rectangular aperture 100, Figure 4, bordered at each side by an upwardly extending frame member 101. The aperture 100 is for the purpose of passing the follower lug 55 so that it may come into engagement with the cam 48.

The aperture 100 is also large enough so that the upper part or dwell 52, of the cam 48, may project through it, as shown in Figure 4. The frame members 101 are preferably provided on each side with forwardly projecting substantially triangular guide flanges, 102, 103, Figure 1, Figure 3.

These flanges on the fixed jaw 39 cooperate with the movable jaw 40 to prevent the line conductor from coming up into contact with the follower 55, since the flanges project into position to engage the line conductor when the jaws are open, as shown in Figure 4.

Above the aperture 100 the fixed jaw member 39 is provided with a transverse flat flange 104, joining the upwardly extending frame members 101 and supporting the diagonally extending bearing member 59. This bearing member comprises an integral tubular member, as previously described, with a bore 58 for receiving the shank portion 57 of the operator 20.

The pins 93, Figure 2, comprise integral cylindrical members which project laterally from the flat flange 104 at each side, and are preferably of such length that they do not project beyond the guide flanges 102.

The purpose of the pins 93 is to hold the spring 63 in proper position, and the pins 93 are spaced from the flange 104 by a slot 105 on each side for receiving parts of the spring 63.

On the side of the fixed jaw member 39, toward the operating member 20, the rectangular

frame surrounding the aperture 100 is substantially flat, but it may be provided with projecting lugs 106 on each side (Figure 2) and laterally extending re-enforcing ribs 107 on each side of the body portion 69, these being spaced from each other to provide an upwardly extending groove 108 on each side for receiving the free ends or legs 109, of the spring 63.

The side of the rectangular frame 104 is also preferably provided with a pair of guide lugs 110 above the aperture 100, Figure 2, for the purpose of strengthening the transversely extending frame member, which is grooved or cut away at 111 outwardly of the lugs 110 to provide a plane surface for engaging the spring legs 109.

The spring 63 may consist of a steel spring having a U-shaped portion 112, Figure 4, the yoke 113 of which engages the outside of the movable jaw member 40, Figure 4. From the U-shaped portion 112 the two legs of the spring extend backwardly, being bent at substantially right angles at 114 where they extend over the upper corners of the movable jaw 40 on each side of the upwardly extending ribs 94.

From the bend 114 the spring is formed with a plurality of helical turns, as indicated at 115, on each side and after turning about the pins 93 a plurality of times, such as, for example, three turns, the spring is provided with the downwardly extending radial legs 109.

It should be noted that the helical turns 115 of the spring 63 are preferably made considerably larger than the pins 93, in order to increase the resiliency of the spring and to increase its capability of returning to its original shape. Originally the legs 109 extend radially away from the helical turns 115 of the spring at a point on the periphery which is forwardly of the U-shaped bend 112, so that before tensioning the spring 40 its legs 109 would stick off to the right of Figure 4.

After the spring has been placed upon the pins 93, and the movable jaw has been put in place with its bearing surfaces 97 engaging round parts of the pin 98, then each leg of the spring may be bent outwardly of the guide flanges 102 and pried backwardly by means of a screw driver until it rests with its end in the groove 108, thus placing the necessary tension on the spring.

In some embodiments of the invention the spring may be held in place by grooves for the yoke 113 of the spring, or the projecting pins 93 may be eliminated, but the projecting pins eliminate any possibility of the spring sliding upward off the two clamping members.

The operating member 20 is preferably inserted with its shank 57 in the bearing member 59, the slot 37 passing the lug 43. This should be done before the legs of the spring are tensioned, since the jaws may be separated sufficiently when there is no spring tension to insert the operator. The jaws must be separated to insert the operator because the end stop surface 53, Figure 3, on the dwell of the cam, engages the side stop surface 54 on the follower 55 when the jaws are closed for preventing the operating member 20 from being removed from the clamp in the embodiment of Figures 1 to 5.

The operation of this tap clamp is as follows: The operating member 20 may be rotated counterclockwise while holding the fixed jaw against rotation in order to open the jaws. This may be accomplished manually with a handle such as Figure 8, by means of an operator permanently attached to a pole 29, as shown in Figure 9, by 75 means of a "Universal" pole, as shown in Figure

10, or by a clamp stick engaging the ring 22 of Figure 7.

The spring parts 112 and 109 urge the jaws tightly together, pivoting about an axis which is substantially the axis of the pins 98. As the operator is rotated counterclockwise the rise 51 of the cam 48 engages the follower 55 at the left follower surface 56 and slides against this follower, while pressing the follower in such a direction that the follower recedes in aperture 100, while the movable jaw 49 is pivoted away from the fixed jaw.

The camming action of the rise of the cam against the follower tends to urge the operating member 20 downward but this is resisted by the thrust flange 36, the bottom surface 45 of which slides upon the top 44 of lug 43.

This pivotal movement continues as long as the cam rise 51 is engaging the follower, until the jaws are open to the position of Figure 4, after which continued rotation of the operating member 20 causes the dwell 52 of the cam 48 to engage the follower 55; and at this time the follower has receded until it is out of the aperture 100 and the cam flange 48 is projecting through the aperture 100, as shown in Figure 4.

As the rotation continues the dwell 52 of the cam 48 engages both end surfaces 56 of the follower 55, and since there is no longer any slope engaging the follower there is no tendency for the jaws to react against the cam in such way as to close the jaws. In other words, the dwell of the cam holds the jaws open, and on account of friction between the follower and the cam the parts are firmly held in open position.

The limit of the rotation of the cam is reached when the stop lug 46 has its leading surface 116 engaging the lug 43, beyond the base of the slot 47, as shown in Figure 5 in dotted lines. Thus the stop member 46 prevents the operator from being rotated so far that the follower would pass off the end 53 of the cam.

Assuming that the clamp is to be applied to an energized transmission line, a tap wire such as a ground wire 75 should first be placed in the connector bolt 71 and secured by tightening the nut 82. The other end of the wire may be grounded, the jaws may be opened as described and the ring 22 may be engaged by the jaws 117, 118 of the clamp stick 119.

The clamp stick 119 preferably has a tubular metal head 120, which is provided with a slotted aperture at the upper end for passing the ring 22. Inside the tubular head 120 of the clamp stick there is a rotatable sleeve 122 which also has a slot 123, adapted to register with the slot 121 in one rotative position, and adapted to extend transversely to the slot 121 when the sleeve 122 is turned 90 degrees in the tubular metal head 120.

This rotative motion of the sleeve 122 may be accomplished by providing a slot 124 in the head 120, and by having a screw bolt 125 which projects from the slot and is carried by the sleeve 122. The clamp stick head 120, also preferably has upwardly extending flanges 126 on each side of the end of the head, separated by a slot at 127 for receiving the lug 43 on the fixed jaw.

While the aperture 121 has been described as a slot, it preferably has a rounded portion 128 midway between its ends for receiving the enlargement 35 on the operating member 20. The purpose of the slots 127 which receive the lug 43 of the fixed jaw is as follows:

Tap wires 75 may be relatively heavy and stiff,

and it may be necessary for the operator to twist the entire clamp assembly with the clamp stick to so twist the tap wire 75 against considerable resistance that it is so bent that the open jaws are extended in the right direction to engage the line wire. Once the tap wire 75 has been suitably twisted to line up the jaws with the line wire, the clamp stick can be used to place the movable jaw 49 over the line wire so that the line wire supports both the clamp and the clamp stick. Then the clamp stick can be withdrawn sufficiently so that the lug 43 is out of the slot 127 and the clamp stick engages only the ring 22 of the operating member 20.

15 This ring, however, is retained in the clamp stick head 120 because of the inner sleeve 122, which has been turned until its slotted aperture 123 extends transversely to the slotted aperture 121.

20 The inside of the tubular head 120 is provided with a rounded concavity 129, into which the ring 22 may be pulled, but as the ring is transverse to the elongated slot aperture 121 it cannot come out. Then the lineman may rotate the clamp stick in a clockwise direction, rotating the operating member 20 and causing the cam 48 to turn in such manner that the dwell passes out from under the follower and the follower eventually passes down the rise of the cam while the jaws are closed by the spring.

25 The line wire is then clamped by the jaws under the influence of the spring, and this gives a uniform and lasting contact between the line wire and the clamp which can never be loosened by passage of time, rattling or the like. The spring pressure is taken by the jaws against the line wire and the cam is relieved of load, but the spring 61 in bearing member 59 constantly urges the operating member 20 axially with its thrust flange 36 against thrust lug 43, so that there can be no rattling of the operating member on the line.

30 The friction of the flange 36 against stop member 43 is such that the cam does not tend to rotate either. Referring now to Figure 6, this figure discloses an operator 20a of slightly different form. It has the same ring 22 and shank 21, thrust flange 36 and cam 48, but the shank extension 57a above the cam is preferably longer and provided with a slightly tapered portion 57b. 35 The reason for this is that the operator 20a is intended to be removed after the clamp is placed on the line, and re-inserted when the clamp is to be removed from the line.

35 Thus the tapered portion 57b is easier to insert into the bore 58 than it would be if it did not have such a tapered portion. Also the bore 58 in the bearing member 59 is a through bore, permitting the use of a longer shank portion 57a, 57b.

40 In the clamp of Figures 1 to 5, the clearance slot 37 for passing the lug 43 is also so located that the operating member 20 cannot be removed from the assembly until the jaws are wide open and actually opened to a position beyond that shown in Figure 4. That position is most easily attained by first removing the spring, and the reason for this is that the operator 20, of Figures 1 to 5, is not intended to be removed from the clamp assembly except when one is trying to disassemble the device.

45 In the device of Figure 6, the clearance slot 37a is located, as shown in Figure 11, so that it registers with the lug 43 when the jaws are closed. When the jaws have been opened and the spring strain is taken by a line conductor between the 50 jaws, then the cam 48 of operator 20a is relieved

11

of its strain and it may be turned back to the original position of the operator 20a, where the slot 31a registers with lug 43, and the operator 20a may be removed by merely pulling downward.

Thus the operator 20a may be removed after the clamp of Figure 6 has been placed on the line, and this clamp has the advantage that it will be cheaper because it is not necessary to provide an operator for every clamp. One or two operators may serve the purpose of applying and removing a great many clamps, and the operator becomes a tool that is carried in the tool box and used when it is necessary to apply or remove a clamp.

Such clamps are cheaper because they have the advantage that they cannot be removed except by one who has a suitable operating member 20a. Such an operating member 20a may also have its lower end provided with the handle 23 of Figure 8, or the ferrule 26 of Figure 9, so that it is permanently attached to a pole 29. Or the operator 20a may have the "Universal" pole flange 31 of Figure 10, so that it becomes a small tool that can be added to or removed from a "Universal" pole.

The operator 20a is preferably so constructed that it may be used with a clamp stick of the type which has clamping jaws that are drawn into a sleeve like the sleeve 120 of Figure 1. In such case provision is preferably made on the operating member 20a for permitting the clamp stick head to twist the tap wire.

Such a provision may be made on the operating member 20a, providing an enlargement 130 above the shank portion 21 and below the thrust flange 36, Figure 6. This enlargement 130 has a pair of laterally projecting ribs 131, which are integrally attached to the shank 21 and to a radially projecting rib 132.

The ribs 131 serve to engage in the slots 127 of the clamp stick head when the ring 22 is drawn into the clamp stick head. The elongated stop flange 133, above the ribs 131, engages the top of the clamp stick and prevents the eye from being drawn into the clamp stick any farther.

The construction of the clamp stick, which may be like any of those of the prior art of this type, is such that under these conditions the operating member 20 is rigidly secured in the end of the clamp stick. Such rigid securing is essential since the tapered end 57b of the operator 20a must be pointed toward the bore 58 of bearing 59 to insert the operator.

Aside from the fact that the operator of Figure 6 is removable, the device of Figure 6 operates in every way substantially like that of Figures 1 to 5.

It will thus be observed that I have invented an improved hot wire clamp which provides a constant resilient engagement with the line wire, and which can be applied or removed by means of an operator having a cam for camming the two jaws apart against the pressure of a spring.

There is no danger of the present clamp losing its characteristics due to corrosion, as the existence of a slight amount of corrosion on the cam will not prevent it from performing its function.

The bearing which rotatably supports the operating member is open downwardly so that water and dirt will not tend to get in the bearing, and corrosion at this point is minimized. There is no danger of the clamp being loosened

12

by vibration, nor does the clamp place undesirable strains on the line conductor in the course of its application or removal.

The present clamp may be embodied in a form which permits the removal of the operating member, thus reducing the number of parts of the clamp, since one operating member may be used for many clamps. This also reduces the cost of the device and reduces the weight on the line, and prevents anyone from tampering with the clamp on the line who does not have an operating member particularly adapted to be used with the clamp.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a hot wire clamp, the combination of a fixed jaw member and a movable jaw member, said jaw members having pivotal engagement with each other at one end, and being provided with clamping surfaces for engaging a line wire at a point spaced from said point of pivotal engagement, connector means carried by one of said jaws for engagement with a tap wire, and an operating member comprising a shaft rotatably mounted in a bearing in the fixed jaw member and having a cam engaging an integral follower carried by the movable jaw member, the said cam having a helical portion with a rise that acts in an axial direction, and said cam moving said movable jaw member from the closed to the open position upon rotation of said shaft, and resilient means for urging the jaws into closed position, said operating member being provided with a radially projecting flange below said cam, and said fixed jaw member having a stop lug located below said flange, the flange of said operating member reacting against said lug when the cam acts on the follower.

2. In a hot wire clamp, the combination of a fixed jaw member and a movable jaw member, said jaw members having pivotal engagement with each other at one end, and being provided with clamping surfaces for engaging a line wire at a point spaced from said point of pivotal engagement, connector means carried by one of said jaws for engagement with a tap wire, and an operating member comprising a shaft rotatably mounted in a bearing in the fixed jaw member and having a cam engaging an integral follower carried by the movable jaw member, the said cam having a helical portion with a rise that acts in an axial direction, and said cam moving said movable jaw member from the closed to the open position upon rotation of said shaft, and resilient means for urging the jaws into closed position, said operating member being provided with a radially projecting flange below said cam, and said fixed jaw member having a stop lug located below said flange, the flange of said operating member reacting against said lug when the cam acts on the follower, the said flange being provided with a radial slot for passing said lug when the operating member is in a predetermined rotative position.

3. In a hot wire clamp, the combination of a fixed jaw member comprising a metal member formed with a downward extension carrying a

connector for a tap wire, said fixed jaw having an upwardly extending frame surrounding an aperture for passing a follower, said frame supporting a diagonally extending bearing member and having pivot surfaces on opposite sides of said bearing member, a movable jaw member provided at its upper end with concave bearing surfaces for engaging said first-mentioned pivot surfaces to pivot the movable jaw on the fixed jaw, the said jaws being provided with opposed wire clamping surfaces, spring means having coiled portions adjacent said pivot surfaces and having radially projecting legs engaging outside the movable jaw and outside the fixed jaw to urge them together, said movable jaw having a follower projecting through said aperture and an operating member having a shaft in said diagonal bearing and having a cam for engaging said follower, said cam urging said movable jaw to open position upon rotation of the operating member, the said cam comprising a peripherally extending flange carried by the operator shaft, and having a substantially helical portion serving as a rise of the cam.

4. In a hot wire clamp, the combination of a fixed jaw member comprising a metal member formed with a downward extension carrying a connector for a tap wire, said fixed jaw having an upwardly extending frame surrounding an aperture for passing a follower, said frame supporting a diagonally extending bearing member and having pivot surfaces on opposite sides of said bearing member, a movable jaw member provided at its upper end with concave bearing surfaces for engaging said first-mentioned pivot surfaces to pivot the movable jaw on the fixed jaw, the said jaws being provided with opposed wire clamping surfaces, spring means having coiled portions adjacent said pivot surfaces and having radially projecting legs engaging outside the movable jaw and outside the fixed jaw to urge them together, said movable jaw having a follower projecting through said aperture and an operating member having a shaft in said diagonal bearing and having a cam for engaging said follower, said cam urging said movable jaw to open position upon rotation of the operating member, the said cam comprising a peripherally extending flange carried by the operator shaft, and having a substantially helical portion serving as a rise of the cam, the said cam also having a substantially flat portion serving as a dwell to hold the jaws open.

5. In a hot wire clamp, the combination of a fixed jaw member comprising a metal member formed with a downward extension carrying a connector for a tap wire, said fixed jaw having an upwardly extending frame surrounding an aperture for passing a follower, said frame supporting a diagonally extending bearing member and having pivot surfaces on opposite sides of said bearing member, a movable jaw member provided at its upper end with concave bearing surfaces for engaging said first-mentioned pivot surfaces to pivot the movable jaw on the fixed jaw, the said jaws being provided with opposed wire clamping surfaces, spring means having coiled portions adjacent said pivot surfaces and having radially projecting legs engaging outside the movable jaw and outside the fixed jaw to urge them together, said movable jaw having a follower projecting through said aperture and an operating member having a shaft in said diagonal bearing and having a cam for engaging said follower, said cam urging said movable jaw to open position upon rotation of the operating member, the said cam comprising a peripherally

extending flange carried by the operator shaft, and having a substantially helical portion serving as a rise of the cam, the said cam also having a substantially flat portion serving as a dwell to hold the jaws open, the said operating member being provided below said cam with a thrust flange, and said fixed jaw member having a lug engaging below said thrust flange for reaction of the thrust flange against said lug when the cam is acting, said thrust flange and lug also serving to hold the operator and jaws in assembly, and said thrust flange having a radial slot located to pass said lug when the operating member is in a predetermined rotative position, the said slot being so located that it may be registered with said lug when the jaws are closed on themselves or upon a line wire.

6. In a hot wire clamp, the combination of a fixed jaw member comprising a metal member formed with a downward extension carrying a connector for a tap wire, said fixed jaw having an upwardly extending frame surrounding an aperture for passing a follower, said frame supporting a diagonally extending bearing member and having pivot surfaces on opposite sides of said bearing member, a movable jaw member provided at its upper end with concave bearing surfaces for engaging said first-mentioned pivot surfaces to pivot the movable jaw on the fixed jaw, the said jaws being provided with opposed wire clamping surfaces, spring means having coiled portions adjacent said pivot surfaces and having radially projecting legs engaging outside the movable jaw and outside the fixed jaw to urge them together, said movable jaw having a follower projecting through said aperture and an operating member having a shaft in said diagonal bearing and having a cam for engaging said follower, said cam urging said movable jaw to open position upon rotation of the operating member, the said cam comprising a peripherally extending flange carried by the operator shaft, and having a substantially helical portion serving as a rise of the cam, the said cam also having a substantially flat portion serving as a dwell to hold the jaws open, the said operating member being provided below said cam with a thrust flange, and said fixed jaw member having a lug engaging below said thrust flange for reaction of the thrust flange against said lug when the cam is acting, said thrust flange and lug also serving to hold the operator and jaws in assembly, and said thrust flange having a radial slot located to pass said lug when the operating member is in a predetermined rotative position, the said slot being so located that it comes into registry with said lug only when the jaws are wide open beyond the maximum travel of the jaws when actuated by the cam.

7. In a hot wire clamp, the combination of a fixed jaw member and a movable jaw member, said jaw members having pivotal engagement with each other at one end, and being provided with clamping surfaces for engaging a line wire at a point spaced from said point of pivotal engagement, connector means carried by one of said jaws for engagement with a tap wire, an integral bearing carried by the fixed jaw member at its upper end and having its axis extending transversely to the movable jaw member, an integral follower carried by the movable jaw member, and an operating member comprising a shaft having a shank at its upper end rotatably mounted in said bearing in the fixed jaw member, said shank carrying an integral helical cam flange, the side of said cam flange engaging said follower, and the

15

rotation of said operating member causing said cam to move said movable jaw member from the closed to the open position, said fixed jaw having a thrust lug extending toward said shank, and said operating member having a radially extending thrust flange engaging the upper side of said thrust lug so that the operating member may react against the thrust lug at said radial flange when the helical cam flange acts on the movable jaw member, said thrust flange having a radial slot for passing said thrust lug, said slot being located to pass said lug when the jaws are opened to maximum position so that the operating member cannot be removed when the clamp is on the line.

8. An operating member for clamp connectors, comprising an elongated cylindrical shank, said shank being provided with an integral radially projecting cam member having a helical flange serving as a riser for engaging a follower upon a movable clamping member, the said shank extending outwardly from said cam and having a pointed cylindrical portion for insertion into a cylindrical bearing in the fixed clamping member of a tap clamp, the said operating member having on its shank below said cam an integral radially extending thrust flange for engaging a thrust lug on a fixed clamping member, and being provided at its lower end with a head for attachment to an insulating operating pole.

9. An operating member for clamp connectors, comprising an elongated cylindrical shank, said shank being provided with an integral radially projecting cam member having a helical flange serving as a riser for engaging a follower upon a movable clamping member, the said shank extending outwardly from said cam and having a pointed cylindrical portion for insertion into a cylindrical bearing in the fixed clamping member of a tap clamp, the said operating member having on its shank below said cam an integral radially extending thrust flange for engaging a thrust lug on a fixed clamping member, and being

16

provided at its lower end with a head for attachment to an insulating operating pole, said thrust flange being provided at one side with a radial slot for passing said thrust lug, to permit the removal of the operating member when it is rotated with its slot in registry with the thrust lug.

10. An operating member for clamp connectors, comprising an elongated cylindrical shank, said shank being provided with an integral radially projecting cam member having a helical flange serving as a riser for engaging a follower upon a movable clamping member, the said shank extending outwardly from said cam and having a pointed cylindrical portion for insertion into a cylindrical bearing in the fixed clamping member of a tap clamp, the said operating member having on its shank below said cam an integral radially extending thrust flange for engaging a thrust lug on a fixed clamping member, and being provided at its lower end with a head for attachment to an insulating operating pole, the said head comprising an integral ring formation of a size adapted to be engaged by a standard clamp stick, the said shank also having between the ring and the thrust flange an integral enlargement formed with a depending radially projecting rib for engagement in the upper slot in a clamp stick.

HENRY W. BODENDIECK.
